DRIVING MECHANISM FOR ROLLING DOORS
AND THE LIKE

Nathan Michelman, Brooklyn, N. Y.

Application January 9, 1952, Serial No. 265,679

12 Claims. (Cl. 74—625)

1

This invention relates to rolling doors of the type arranged to be wound upon and unwound from a drum at the head of a doorway, and more particularly to an improved operating mechanism for winding and unwinding such doors.

The winding drums of such doors, particularly when the doors are of the heavier type, are operated by a geared electric motor drive controlled from a suitable "open" and "close" switch. Limit switch arrangements are provided to open the motor circuit automatically as the door reaches either limit of movement, and automatically operated brake means are associated with the drum to stop the door movement and to retain the door in operated position.

To operate the door in the event of power or motor failure, manual drive means are usually provided. In some cases, the manual drive is entirely independent of the motor drive, resulting in increased weight and cost of the operating parts. When the manual drive means is incorporated into the motor drive means, difficulties are presented in providing for proper independent operation of the two drives.

The present invention is directed to a novel combined motor and manual drive for such doors in which cutting out of the motor drive and release of the brake are easily and simply effected in a novel manner when manual operation is desired. The manual operation is usually applied through an endless chain dependent from the door operating mechanism, and the present invention provides a pendant element adjacent the chain and which is merely pulled to cut out the motor and release the brake for manual operation.

For an understanding of the invention principles, reference is made to the following description of a typical embodiment thereof as illustrated in the accompanying drawings.

In the drawings:

Fig. 1 is a side elevation view of a rolling door operating mechanism embodying the invention;

Fig. 2 is a front elevation of the mechanism;

Fig. 3 is a rear elevation view of a detail of the mechanism; and

Fig. 4 is an elevation view of a connection between the drum driving shaft and a driving gear.

Referring more particularly to Fig. 2, a rolling door 10 is secured to a drum 11 coaxially mounted on a shaft 12, the door, drum, and major portion of shaft 12 being protected by a casing 13. Suitable counter-balancing mechanism (not shown) may be provided for the door. The outer end of shaft 12 has an externally threaded sleeve

15 pinned thereto as at 14 (Fig. 4). Sleeve 15 has longitudinal ribs 16 thereon engaged in keyways 17 in a drive gear 20, sleeve 15 having a clearance fit through gear 20. Gear 20 is disposed in a gear housing 18.

The outer end of shaft 12 has a head 21 engaging a head 22 on a stud shaft 23 secured by a nut 24 in an arched bracket 26 on housing 18. Spaced from shaft 12, and parallel therewith, is a drive shaft 27 having a grooved driven pulley 25 on its outer end and a pinion 28 rotatable therewith. Pinion 28 meshes with a gear 31 rotatable with a pinion 32 meshing with gear 20, the whole constituting a reduction gearing in housing 18.

Pulley 25 is driven by a V-belt 36 trained over a driving pulley 30 of a motor 35. The latter is mounted on a bracket 33 adjustable along rod supports 34 for setting the tension on belt 36.

20 A brake drum 37 is rotatable with pulley 30 and associated with a brake band 38. The latter is normally biased to a drum gripping position by a spring 41 embracing a tie rod 42, the brake being releasable by a toggle 43 operable by a link 44 connected to a lever 46 pivoted at 47 on the motor housing. The left end of lever 46 is secured to the armature 48 of a solenoid 40 mounted on the motor housing. The right end of the lever carries a hook 51 and a spring 52 connected to a dependent chain 50 for a purpose to be described.

25 Operation of motor 35 to either open or close the door is initiated by a suitably positioned "open" and "close" switch connected, through a conduit, to a junction box 53 in turn connected to the motor control 54 through a conduit 56. Whenever motor 35 is energized, solenoid 40 is also energized to move its armature 48 upwardly and swing lever 46 clockwise. Through link 44 and toggle 43, brake band 38 is held released from

30 brake drum 37 during the period motor 35 is energized. When motor 35 is de-energized at either limit of door movement, in a manner to be described, solenoid 40 is simultaneously de-energized, releasing lever 46. Spring 41 and tie rod 42 immediately clamp brake band 38 on drum 37 to arrest the movement of the door through the mechanism connected to motor 35.

35 The motor 35 is automatically cut out by limit switch means operated by threaded sleeve 15. This sleeve which, through shaft 12 rotates with drum 11, is threaded through a plate 57 having a bar 58 extending therefrom. As sleeve 15 rotates in one direction as the door closes, plate 57 is moved outwardly and, as the door reaches

the closed position, bar 58 contacts an adjustable stop 61 on a lever 62 secured to a shaft 63 mounted in a bracket 64 on housing 18. As lever 62 and shaft 63 are swung, a second lever 55 on shaft 63 engages a button 66 of a normally closed limit switch included in the "close" circuit of motor 35. This breaks the motor circuit for closing the door, and the door movement stops.

When the door is moved in the opening direction, rotation of sleeve 15 moves plate 57 inwardly. Bar 58 carries an adjustable stop 67 which, as the door nears the open position, engages the button 68 of a normally closed limit switch in the "open" circuit of motor 35. Thus, when the door reaches the open position, motor 35 is de-energized and braked to arrest the door movement.

Manual operation is effected by means of a dependent endless chain 60 trained over a sprocket 65. Sprocket 65 is mounted on a stub shaft 71 supported in a carrier 72. The latter has sleeves 76 slidably mounted on a pair of rods 73 extending from housing 18, and is normally biased outwardly by springs 74 so that a clutch jaw 75 on shaft 71 is normally disengaged from a clutch jaw 70 on pulley 25.

Rods 73 have fixed thereto bearings 77 carrying a shaft 78. At one end, this shaft has an arm 80 secured to chain 50. Adjacent each rod 73, shaft 78 has affixed thereto members each comprising a cam arm 81 and a stop 82. Also carried by sleeves 76 is an operating lever 83 arranged to engage the operating button 84 of a main normally closed switch included in the energizing circuits of motor 35.

To manually operate the door, chain 50 (which may be a cable or rod) is pulled downwardly and held down while endless chain 60 is operated. Chain 50 swings lever 46 clockwise which, through link 44 and toggle 43, releases brake band 38. Also, arm 80 is swung counter-clockwise (Fig. 2) to correspondingly swing shaft 78. Cam arms 81 engage sleeves 76 to move carrier 72 inwardly, compressing springs 74. Jaws 70 and 75 engage, connecting sprocket 65 to pulley 25 and thus to the gearing, for rotating the door operating drum. As carrier 72 is thus moved inwardly, arm 83 depresses button 84 to cut out the motor circuit.

With chain 50 held down, chain 60 is operated to turn sprocket 65 to operate the door. When the door has been operated to the desired position, chain 50 is released. Springs 74 move carrier 72 outwardly to disengage the clutch 70-75. Stop arms 82 prevent bouncing of the disconnect arrangement by engaging carrier 72 as it reaches its outer limiting position. Brake band 38 is closed by springs 41 and tie rod 42, holding the door against movement and ready for motor operation.

While a specific embodiment of the invention has been shown and described in detail to illustrate the application of the invention principles, it will be understood that the invention may be otherwise embodied without departing from such principles.

What is claimed is:

1. In a driving mechanism for rolling doors, a driven shaft; transmission means connecting said driven shaft to a rolling door shaft; a pulley keyed to said driven shaft; an electric motor driving said pulley; normally engaged brake means associated with said motor; first brake release means connected to said brake means and operable concurrently with energization of said motor

to release said brake means; second brake release means connected to said brake means and manually operable to release said brake means; a manually operable driving wheel coaxial with said pulley and axially displaceable relative thereto; cooperating clutch elements carried by said pulley and said driving wheel; means normally biasing said driving wheel to a position disengaging said clutch elements; a device associated with said driving wheel and effective, when operated, to move said driving wheel to engage said clutch elements; and a manually operable member connected to said second release means and to said device and operable, when actuated, to simultaneously release said brake means and engage said clutch elements for manual operation of the door.

2. In a driving mechanism for rolling doors, a driven shaft; transmission means connecting said driven shaft to a rolling door shaft; a pulley keyed to said driven shaft; an electric motor driving said pulley; normally engaged brake means associated with said motor; first brake release means connected to said brake means and operable concurrently with energization of said motor to release said brake means; second brake release means connected to said brake means and manually operable to release said brake means; a manually operable driving wheel coaxial with said pulley and axially displaceable relative thereto; cooperating clutch elements carried by said pulley and said driving wheel; means normally biasing said driving wheel to a position disengaging said clutch elements; a device associated with said driving wheel and effective, when operated, to move said driving wheel to engage said clutch elements; a manually operable member connected to said second release means and to said device and operable, when actuated, to simultaneously release said brake means and engage said clutch elements for manual operation of the door; a normally closed main switch controlling energization of said motor; and a switch operator connected to said device and actuated, when said device is actuated by said member, to open said switch.

3. In a driving mechanism for rolling doors, a driven shaft; transmission means connecting said driven shaft to a rolling door shaft; a pulley keyed to said driven shaft; an electric motor driving said pulley; normally engaged brake means associated with said motor; first brake release means connected to said brake means and operable concurrently with energization of said motor to release said brake means; second brake release means connected to said brake means and manually operable to release said brake means; a manually operable driving wheel coaxial with said pulley and axially displaceable relative thereto; cooperating clutch elements carried by said pulley and said driving wheel; means normally biasing said driving wheel to a position disengaging said clutch elements; a device associated with said driving wheel and effective, when operated, to move said driving wheel to engage said clutch elements; a manually operable member connected to said second release means and to said device and operable, when actuated, to simultaneously release said brake means and engage said clutch elements for manual operation of the door; a normally closed main switch controlling energization of said motor; a switch operator connected to said device and actuated, when said device is actuated by said member, to open said switch; a pair of limit

switches in the motor energization circuit and respectively opening the motor circuit when the door reaches its limit of movement in either direction; and a limit switch operator driven by the rolling door shaft and effective at either limit of door operation, to open the corresponding limit switch.

4. In a driving mechanism for rolling doors, a driven shaft; transmission means connecting said driven shaft to a rolling door shaft; a pulley keyed to said driven shaft; an electric motor driving said pulley; normally engaged brake means associated with said motor; first brake release means connected to said brake means and operable concurrently with energization of said motor to release said brake means; second brake release means connected to said brake means and manually operable to release said brake means; a manually operable driving wheel coaxial with said pulley and rotatably mounted in a carrier axially displaceable relative to said driven pulley; cooperating clutch elements carried by said pulley and said driving wheel; means normally biasing said carrier to a position disengaging said clutch elements; a shaft fixed relatively to said driven pulley and adjacent said carrier; cam means on said shaft engageable with said carrier to move the latter axially to engage said clutch elements when said shaft is rocked; a radially extending arm fixed to said shaft; and a manually operable member connected to said second release means and to said shaft arm and operable, when actuated, to simultaneously release said brake means and rock said shaft to move said carrier to engage said clutch elements for manual operation of the door.

5. In a driving mechanism for rolling doors, a driven shaft; transmission means connecting said driven shaft to a rolling door shaft; a pulley keyed to said driven shaft; an electric motor driving said pulley; normally engaged brake means associated with said motor; first brake release means connected to said brake means and operable concurrently with energization of said motor to release said brake means, second brake release means connected to said brake means and manually operable to release said brake means; a manually operable driving wheel coaxial with said pulley and rotatably mounted in a carrier axially displaceable relative to said driven pulley; cooperating clutch elements carried by said pulley and said driving wheel; means normally biasing said carrier to a position disengaging said clutch elements; a shaft fixed relatively to said driven pulley and adjacent said carrier; cam means on said shaft engageable with said carrier to move the latter axially to engage said clutch elements when said shaft is rocked; a radially extending arm fixed to said shaft; a manually operable member connected to said second release means and to said shaft arm and operable, when actuated, to simultaneously release said brake means and rock said shaft to move said carrier to engage said clutch elements for manual operation of the door; a normally closed main switch controlling energization of said motor; and a switch operator connected to said shaft and actuated, when said shaft is rocked by said member, to open said switch.

6. In a driving mechanism for rolling doors, a driven shaft; transmission means connecting said driven shaft to a rolling door shaft; a pulley keyed to said driven shaft; an electric motor driving said pulley; normally engaged brake means associated with said motor; a lever piv-

oted adjacent said brake means; linkage interconnecting said lever and brake means and operable to release said brake means when said lever is rocked; brake release means connected to said lever and operable concurrently with energization of said motor to rock said lever to release said brake means; a manually operable driving wheel coaxial with said pulley and axially displaceable relative thereto; cooperating clutch elements carried by said pulley and said driving wheel; means normally biasing said driving wheel to a position disengaging said clutch elements; a device associated with said driving wheel and effective, when operated, to move said driving wheel to engage said clutch elements; and a manually operable member connected to said lever to rock the latter and connected to said device and operable, when actuated, to simultaneously release said brake means and engage said clutch elements for manual operation of the door.

7. In a driving mechanism for rolling doors, a driven shaft; transmission means connecting said driven shaft to a rolling door shaft; a pulley keyed to said driven shaft; an electric motor driving said pulley; normally engaged brake means associated with said motor; a lever pivoted adjacent said brake means; linkage interconnecting said lever and brake means and operable to release said brake means when said lever is rocked; brake release means connected to said lever and operable concurrently with energization of said motor to rock said lever to release said brake means; a manually operable driving wheel coaxial with said pulley and rotatably mounted in a carrier axially displaceable relative to said driven pulley; cooperating clutch elements carried by said pulley and said driving wheel; means normally biasing said carrier to a position disengaging said clutch elements; a shaft fixed relatively to said driven pulley and adjacent said carrier; cam means on said shaft engageable with said carrier to move the latter axially to engage said clutch elements when said shaft is rocked; a radially extending arm fixed to said shaft; and a manually operable member connected to said lever to rock the latter and connected to said device shaft arm and operable, when actuated, to simultaneously release said brake means and rock said shaft to move said carrier to engage said clutch elements for manual operation of the door.

8. In a driving mechanism for rolling doors, a driven shaft; transmission means connecting said driven shaft to a rolling door shaft; a pulley keyed to said driven shaft; an electric motor driving said pulley; normally engaged brake means associated with said motor; a lever pivoted adjacent said brake means; linkage interconnecting said lever and brake means and operable to release said brake means when said lever is rocked; brake release means connected to said lever and operable concurrently with energization of said motor to rock said lever to release said brake means; a manually operable driving wheel coaxial with said pulley and rotatably mounted in a carrier axially displaceable relative to said driven pulley; cooperating clutch elements carried by said pulley and said driving wheel; means normally biasing said carrier to a position disengaging said clutch elements; a shaft fixed relatively to said driven pulley and adjacent said carrier; cam means on said shaft engageable with said carrier to move the latter axially to engage said clutch elements when said shaft is rocked;

a radially extending arm fixed to said shaft; a manually operable member connected to said lever to rock the latter and connected to said device shaft arm and operable, when actuated, to simultaneously release said brake means and rock said shaft to move said carrier to engage said clutch elements for manual operation of the door; a normally closed main switch controlling energization of said motor; and a switch operator connected to said shaft and actuated, when said shaft is rocked by said member, to open said switch.

9. In a driving mechanism for rolling doors, a driven shaft; transmission means connecting said driven shaft to a rolling door shaft; a pulley keyed to said driven shaft; an electric motor driving said pulley; normally engaged brake means associated with said motor; a lever pivoted adjacent said brake means; linkage interconnecting said lever and brake means and operable to release said brake means when said lever is rocked; brake release means connected to said lever and operable concurrently with energization of said motor to rock said lever to release said brake means; a manually operable driving wheel coaxial with said pulley and rotatably mounted in a carrier axially displaceable relative to said driven pulley; cooperating clutch elements carried by said pulley and said driving wheel; means normally biasing said carrier to a position disengaging said clutch elements; a shaft fixed relatively to said driven pulley and adjacent said carrier; cam means on said shaft engageable with said carrier to move the latter axially to engage said clutch elements when said shaft is rocked; a radially extending arm fixed to said shaft; a manually operable member connected to said lever to rock the latter and connected to said device shaft arm and operable, when actuated, to simultaneously release said brake means and rock said shaft to move said carrier to engage said clutch elements for manual operation of the door; a normally closed main switch controlling energization of said motor; a switch operator connected to said shaft and actuated, when said shaft is rocked by said member, to open said switch; a pair of limit switches in the motor energization circuit and respectively opening the motor circuit when the door reaches its limit of movement in either direction; and a limit switch operator driven by the rolling door shaft and effective, at either limit of door operation, to open the corresponding limit switch.

10. In a driving mechanism for rolling doors, a driven shaft; transmission means connecting said driven shaft to a rolling door shaft; a pulley keyed to said driven shaft; an electric motor driving said pulley; normally engaged brake means associated with said motor; first brake release means connected to said brake means and operable concurrently with energization of said motor to release said brake means; second brake release means connected to said brake means and manually operable to release said brake means; a manually operable driving wheel coaxial with said pulley and axially displaceable relative thereto; cooperating clutch elements carried by said pulley and said driving wheel; means normally biasing said driving wheel to a position disengaging said clutch elements; a device associated with said driving wheel and effective, when operated, to move said driving wheel to engage said clutch elements; a manually operable member connected to said second release means and to said device and

operable, when actuated, to simultaneously release said brake means and engage said clutch elements for manual operation of the door; a normally closed main switch controlling energization of said motor; a switch operator connected to said device and actuated, when said device is actuated by said member, to open said switch; a pair of limit switches in the motor energization circuit and respectively opening the motor circuit when the door reaches its limit of movement in either direction; a threaded sleeve rotatable with the rolling door shaft; a non-rotatable element threaded on said sleeve for axial movement therealong when said door shaft is rotated, and a switch operator fixed to said element and effective, at either limit of door operation, to open the corresponding limit switch.

11. In a driving mechanism for rolling doors, a driven shaft; transmission means connecting said driven shaft to a rolling door shaft; a pulley keyed to said driven shaft; an electric motor driving said pulley; normally engaged brake means associated with said motor; first brake release means connected to said brake means and operable concurrently with energization of said motor to release said brake means; second brake release means connected to said brake means and manually operable to release said brake means; a manually operable driving wheel coaxial with said pulley and axially displaceable relative thereto; cooperating clutch elements carried by said pulley and said driving wheel; means normally biasing said driving wheel to a position disengaging said clutch elements; a device associated with said driving wheel and effective, when operated, to move said driving wheel to engage said clutch elements; a manually operable member connected to said second release means and to said device and operable, when actuated, to simultaneously release said brake means and engage said clutch elements for manual operation of the door; a normally closed main switch controlling energization of said motor; a switch operator connected to said device and actuated, when said device is actuated by said member, to open said switch; a pair of limit switches in the motor energization circuit and respectively opening the motor circuit when the door reaches its limit of movement in either direction; a threaded sleeve rotatable with the rolling door shaft; a non-rotatable element threaded on said sleeve for axial movement therealong when said door shaft is rotated; a switch operator fixed to said element; and a pair of adjustable abutments carried by said operator and respectively positioned to engage and operate the corresponding limit switches at either limit of door operation to open the motor circuit.

12. In a driving mechanism for rolling doors, a driven shaft; transmission means connecting said driven shaft to a rolling door shaft; a pulley keyed to said driven shaft; an electric motor driving said pulley; normally engaged brake means associated with said motor; a lever pivoted adjacent said brake means; linkage interconnecting said lever and brake means and operable to release said brake means when said lever is rocked; brake release means connected to said lever and operable concurrently with energization of said motor to rock said lever to release said brake means; a manually operable driving wheel coaxial with said pulley and rotatably mounted in a carrier axially displaceable relative to said driven pulley; cooperating clutch

elements carried by said pulley and said driving wheel; means normally biasing said carrier to a position disengaging said clutch elements; a shaft fixed relatively to said driven pulley and adjacent said carrier; cam means on said shaft engageable with said carrier to move the latter axially to engage said clutch elements when said shaft is rocked; a radially extending arm fixed to said shaft; a manually operable member connected to said lever to rock the latter and connected to said device shaft arm and operable, when actuated, to simultaneously release said brake means and rock said shaft to move said carrier to engage said clutch elements for manual operation of the door; a normally closed main switch controlling energization of said

15

motor; a switch operator connected to said shaft and actuated, when said shaft is rocked by said member, to open said switch; a pair of limit switches in the motor energization circuit and respectively opening the motor circuit when the door reaches its limit of movement in either direction; a threaded sleeve rotatable with the rolling door shaft; a non-rotatable element threaded on said sleeve for axial movement therealong when said door shaft is rotated; and a switch operator fixed to said element and effective, at either limit of door operation, to open the corresponding limit switch.
